UNITED STATES PATENT OFFICE.

GREGORY BROWN, OF BROOKLYN, NEW YORK, ASSIGNOR TO WESTERN ELECTRIC COMPANY, OF NEW YORK, N. Y., A CORPORATION OF ILLINOIS.

IMPULSE-TRANSMITTER FOR SELECTIVE SYSTEMS.

1,155,640.

Specification of Letters Patent.

Patented Oct. 5, 1915.

Application filed July 11, 1910. Serial No. 571,397.

To all whom it may concern:

Be it known that I, GREGORY BROWN, citizen of the United States, residing at Brooklyn, in the county of Kings and State of New York, have invented a certain new and useful Improvement in Impulse-Transmitters for Selective Systems, of which the following is in full, clear, concise, and exact description.

- 10 My invention relates to an impulse transmitter for use in connection with party line or like systems wherein there are a plurality of subscriber or way stations on the same line, each station being provided with a selector mechanism adapted in response to impulses set over the line to close a signaling circuit at that station; the number of impulses for calling the stations being different for each particular selector.
- 15 My invention has for its object the provision of an impulse transmitter which will be compact, sure and quiet in its operation, easily manufactured and one which can be easily and speedily adjusted to cause any 20 particular selector on the line to operate its signal.
- 25

The impulse transmitter to which this invention relates comprises in general a clock-work mechanism in which energy is stored up by the turning of a handle which winds a spiral spring. When the handle is released the spring revolves a shaft upon which is mounted a toothed wheel adapted to operate a spring contact for interrupting a circuit.

30 An adjustable member is provided for covering certain of the teeth in such a manner that the number of impulses sent over the line for signaling purposes can be easily varied thus enabling the station at which 35 such an impulse transmitter is located to adjust the apparatus to call any other party on the same line.

In the drawings illustrating my invention: Figure 1 is a view in side elevation 45 of the mechanism with a part of the casing removed. Fig. 2 is a fragmentary detail view of the mechanism looking at it from the bottom. Fig. 3 is a view looking at the inner end of the mechanism. Fig. 4 is a 50 view in front elevation of the inclosing casing. Fig. 5 is a fragmentary detail view of a modified form of key. Fig. 6 is a view in end elevation of the parts shown in Fig. 5. Fig. 7 is a view of the inner end of the 55 modified mechanism.

The two mechanisms herein shown differ only in certain details hereinafter pointed out and the same reference numerals designate like parts in the two arrangements unless otherwise specified.

In said drawings 5 and 6 designate frame plate members secured together by rods 7, 8 and 9. Supported in these frame plates 5 and 6 are shafts 10 and 11, the shaft 10 constituting a driving and the shaft 11 the driven shaft of the mechanism. Loosely mounted upon the shaft 10 is a gear wheel 14 adapted to be driven by a spiral spring 15 on said shaft. Said gear wheel 14 meshes with a pinion 16 on the shaft 11 which pinion is secured to a gear wheel 17 on said shaft 11, said gear wheel 17 being in mesh with a pinion 18 loosely mounted upon the shaft 10 and secured to a gear wheel 19. Said gear wheel 19 in turn meshes with a pinion 20 loosely mounted upon the shaft 11 and secured to a gear 21. The gear 21 meshes with a worm on a governor shaft 22 which is arranged at right angles to the shafts 10 and 11 and supported between arms 23, 23 formed integrally with the frame plate 6. The governor consists of two weighted spring arms 24 and 25 which as the governor shaft 22 is rotated are caused to throw the weights outwardly against the inner face of a metal drum 26, the friction of the weights and drum tending to retard the movement of the rotating parts and keep them at a constant speed.

The specific arrangement of parts whereby the current is interrupted to cause impulses to be sent out on the line is as follows: Mounted upon the inner end of the shaft 11 beyond the frame plate 6 is a wheel 30 having formed on the larger portion of its periphery a plurality of teeth 31, 31 which are adapted to coöperate with spring contacts 32 and 33 to alternately make and break a circuit. As shown the wheel 30 is provided with a portion 34 which is free from teeth, the radius of which is the same as the radius of the wheel at the base of the teeth 31, 31. In this space the lower contact spring 32 rests when the mechanism is in its normal position. Just adjacent to one end of the portion 34 is a tooth 35 having a wider face than the teeth 31, 31 and it is this tooth which first passes under the spring contact 32 as the wheel 30 starts to rotate, the purpose of this wider face tooth 35 be-

ing to keep current on the line a sufficient length of time to cause the operation of a slow acting magnet. Each tooth after the first which passes under the spring contact 32 causes a short interval impulse to go over the line to the selector, causing one step. The number of teeth which pass under said contacted spring is determined by means of an adjustable plate or segment 38 mounted 10 adjacent to the end of the wheel 30 with its periphery flush with the outer edge or tops of the teeth. As shown the segment or plate 38 has a periphery of a length equal to the width of several teeth and when brought under the spring contact 32 causes the closure of the circuit for a considerable length of time, as compared with the closure caused by a single tooth, and causes the sounding of a signal at a waystation.

16 As hereinbefore stated each selector on the line is responsive to a different number of impulses to close the signaling circuit at the particular waystation with which it is associated and the segment or plate 38 is made 25 adjustable in order that any one of said stations may be called by the use of this sending key.

The features of construction whereby the number of impulses to be sent out are determined are as follows: The plate or segment 38, secured to a gear 45 which is rotatably mounted upon the inner end of the shaft 11. A second gear 46 of the same diameter as the gear 45 and meshing therewith is secured to 35 a shaft 47 upon the opposite end of which is mounted a knob 48 for turning said shaft. Secured to one face of the plate or segment 38 is a positioning spring 50, one end of which is depressed or formed to engage between the teeth of the wheel 30 to retain said segment in its adjusted position and cause it to rotate with the wheel 30 during the calling of a station. The end of the shaft 47 upon which is mounted the knob 48 extends through a mounting plate 51 upon the inner face of which is mounted the frame embracing the plates 5 and 6. Upon its outer face said plate 51 is provided with an index for designating the station for which 50 the mechanism is set.

The toothed wheel 30 is adapted to make one complete revolution each time a call is made and in this connection is provided on one face with a projecting stop pin 60 adapted 55 to engage a movable stop lug 61 carried by the shaft 10. In the operation of these particular parts the shaft 10 is turned until the stop lug 61 comes into contact with a stop pin 62 projecting from the frame plate 6. 60 When the handle is released the two shafts 10 and 11 travel at such relative speed that the wheel 30 is caused to make one complete revolution while the stop lug 61 is moving back into position to engage the stop pin 60 on said wheel. The shaft 10 projects through

the mounting plate 51 and is provided thereon with a handle 63 for turning said shaft.

The spring contacts 32 and 33 are mounted upon a supporting lug 70 formed integrally with the frame plate 6, one of said contacts being electrically connected with said frame through the toothed wheel 30 and the other of said springs being electrically connected with a lug 71 insulated from the frame. The plate 51 is adapted to be mounted in a suitable casing or box with the frame thereof in contact with one terminal spring, while the lug 11 is adapted to engage another terminal spring.

Instead of using a single impulse transmitter as hereinbefore described for calling all of the stations on the line there may be used an individual impulse transmitter for each party. Such a selector is illustrated in Figs. 5, 6 and 7 and differs from that hereinbefore described in the arrangement of the segmental plate for determining the impulses, and the arrangement for mounting the mechanism. As shown in said Fig. 7, the individual impulse transmitter is not equipped with the extra shaft and gear wheels for adjusting the position of the segmental plate but instead a segmental plate 80 corresponding with the segmental plate 38 hereinbefore referred to is pivotally mounted upon the end of the shaft 10 in juxtaposition to the toothed wheel 30 and is provided with an arcuated slot 81 concentric with said shaft. A screw 82 passing through said slot into the face of said toothed wheel is adapted to secure said plate in its adjusted position.

The individual keys are each mounted upon a plate 85, this plate being arranged to lock to a suitable framework. As shown the locking means comprises a spring latch member 87 adapted to be turned into a horizontal position to engage frame bars 88, 88, said spring latch 87 being mounted upon the inner end of a screw 89 which extends 100 through the mounting plate 85 with the screw head on the outside of said plate.

The operation of the mechanism hereinbefore described is as follows: Assume that it is desired to signal say party #10 on the line with the mechanism first described. The knob 48 will first be turned until an indicator thereon points to the numeral 10 on the dial plate. This will move the segment 38 to a position where the first ten teeth of the contact wheel will operate the spring contact before it is brought into engagement with said segment. This operation will cause ten current impulses to go out over the line and the selector at station #10 will 115 close a signaling contact which will remain closed during the time that the segment 38 is passing under the spring 32. The passing of the teeth beyond the segment under the spring 32 will step the selector around 120 125 130

without affecting the waystation circuits. When the individual transmitters are used each will have its segment adjusted for a single station, the operation however being 5 the same as that previously described. The arrangement of the impulse transmitter whereby the gears and pinions constituting principal parts of the clock train are all mounted upon two shafts is of advantage 10 inasmuch as it gives a compact structure which can be conveniently mounted in a comparatively small space.

I claim:

1. In an impulse transmitter the combination with a rotatable toothed wheel, of contact springs engaged by the teeth of said wheel to make and break a circuit, a shaft upon which said toothed wheel is mounted, a segmental plate rotatably mounted upon 15 the end of said shaft adjacent to said toothed wheel the periphery of said plate being flush with the outer ends of teeth on said wheel and a positioning spring secured to said plate and provided on one end with a portion adapted to engage the space between two adjacent teeth.
2. In an impulse transmitter the combination with a rotatable toothed wheel and spring contacts engaged thereby for making and breaking a circuit, of a shaft for said toothed wheel, a gear wheel rotatively mounted upon said shaft adjacent to said toothed wheel, a segmental plate secured to 20
- 25

said gear wheel adjacent to said toothed wheel, the curved portion of said segmental plate being flush with the outer ends of teeth on said toothed wheel, a second gear meshing with the gear on the toothed wheel shaft, a shaft for said second gear and a knob for turning said shaft.

3. In an impulse transmitter the combination with a driving shaft and a driven shaft, of a motor spring surrounding said driving shaft, a gear on said driving shaft, a pinion secured to said driven shaft with 40 which said gear meshes, a gear on said driven shaft adapted to rotate with said pinion, a pinion loosely mounted on said driving shaft with which said gear on the driven shaft meshes, a gear rotating with 45 said pinion on said driving shaft, a pinion loosely mounted on said driven shaft with which the loose gear on said driving shaft meshes, a gear mounted to rotate with said loose pinion on said driven shaft, a governor shaft mounted at right angles to said driven shaft and a worm on said governor shaft meshing with said loose gear on said driven shaft.

In witness whereof, I hereunto subscribe 50 my name this 9th day of July, 1910.

GREGORY BROWN.
